US0D1061026S

(12) **United States Design Patent** (10) **Patent No.:** **US D1,061,026 S**
(45) **Date of Patent:** **** Feb. 11, 2025**

(54) **TRUNK**

(71) Applicant: **G.T. LINE—S.R.L.**, Valsamoggia (IT)

(72) Inventor: **Massimo Tonelli**, Bologna (IT)

(73) Assignee: **G.T. LINE—S.R.L.**, Valsamoggia (IT)

(**) Term: **15 Years**

(21) Appl. No.: **29/870,708**

(22) Filed: **Feb. 2, 2023**

(51) **LOC (15) Cl.** **03-01**

(52) **U.S. Cl.**

USPC **D3/276**; D3/905

(58) **Field of Classification Search**

USPC D3/203.1, 203.3, 203.6, 205, 210, 228,

(57) **CLAIM**

The ornamental design for a trunk, as shown and described.

DESCRIPTION

FIG. 1 is a perspective view of the trunk showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof;

FIG. 9 is a bottom perspective view thereof; and,

FIG. 10 is a bottom perspective view thereof.

The broken lines depict portions of the trunk that form no part of the claimed design.

1 Claim, 10 Drawing Sheets
